FIG. 1 is a front view of an electronic light bulb with a
moveable flame of the present disclosure;FIG. 2 is a rear view of the electronic light bulb of FIG. 1;
FIG. 3 is a right side view of the electronic light bulb of FIG.
1;FIG. 4 is a left side view of the electronic light bulb of FIG. 1;
FIG. 5 is a top view of the electronic light bulb of FIG. 1;
FIG. 6 is a bottom view of the electronic light bulb of FIG. 1;
FIG. 7 is a perspective view of the top of the electronic light
bulb of FIG. 1; and,FIG. 8 is perspective view of the bottom of the electronic light
bulb of FIG. 1.The broken lines of FIGS. 1-8 are provided for purposes of
illustration and form no part of the claimed design of the
present application.**1 Claim, 7 Drawing Sheets**(56)
